(57) **CLAIM**

The ornamental design for a packaging for artificial nail adhesive, as shown and described.

DESCRIPTION

FIG. 1 is a perspective top view of a new design for a packaging for artificial nail adhesive, according to one embodiment of our new design;

FIG. 2 is a top view thereof;

FIG. 3 is a bottom view thereof;

FIG. 4 is a front view thereof;

FIG. 5 is a rear view thereof;

FIG. 6 is a right side view thereof; and

FIG. 7 is a left side view thereof.

FIG. 8 is a perspective top view of a new design for a packaging for artificial nail adhesive, according to a second embodiment of our new design;

FIG. 9 is a top view thereof;

FIG. 10 is a bottom view thereof;

FIG. 11 is a front view thereof;

FIG. 12 is a rear view thereof;

FIG. 13 is a right side view thereof; and

FIG. 14 is a left side view thereof.

FIG. 15 is a perspective top view of a new design for a packaging for artificial nail adhesive, according to a third embodiment of our new design;

FIG. 16 is a top view thereof;

FIG. 17 is a bottom view thereof;

FIG. 18 is a front view thereof;

FIG. 19 is a rear view thereof;

FIG. 20 is a right side view thereof; and

FIG. 21 is a left side view thereof.

Broken lines are used to illustrate features of the packaging for artificial nail adhesive that form no part of the claimed design.
